4 Claims. (Cl. 166—29)

This invention relates to a bottom-supported casing. Particularly, the invention relates to a method of anchoring and sealing a large diameter casing in an earth bore hole. In another sense, the invention relates to an anchored casing in an earth bore hole. Most particularly, the invention includes an anchored casing and a method of anchoring a casing particularly adaptable for the anchoring of large diameter casing in an earth bore hole in a manner providing means of compensating for expansion and contraction of the casing as particularly required when such casing is subjected to a high range of temperature variation.

In recent years the use of underground caverns for storing liquids has greatly expanded. One type of liquid which is frequently stored in underground caverns is liquefied petroleum gas, including liquefied natural gas. Liquefied gases must be maintained at very low temperatures. For instance, liquefied natural gas is stored at temperatures approaching minus 250° F. Thus, when liquefied natural gas is injected through a casing into an underground mine or cavern, the temperature of the casing may change as much as 320° F.

Obviously, such large temperature changes will result in a substantial change in the length of the casing, the change being proportional to the total length of the casing.

One of the problems in the use of underground storage facilities is providing a suitable anchor for the large diameter casing positioned in the bore hole leading to the storage facilities. The usual means of anchoring a casing is to support it in the bore hole and pour a hard setting cement grout in the annulus exterior of the casing. This is the usual method in the petroleum industry and works completely satisfactorily where relatively small diameter casing is used and where the casing is not subjected to great temperature changes. However, this method has not proven satisfactory for large diameter casing subject to high ranges of temperatures changes. The expansion and contraction of the casing within hard setting grout ultimately pulls the casing loose from the grout permitting leakage which may permit water from strata above the cavern to flow along the casing and into the cavern. In addition, if the expansion does not pull the casing loose from the grout, the casing may be confined and can be subjected to buckling and so forth.

It is therefore an object of this invention to provide an improved method of anchoring and sealing a casing supported in an earth bore hole.

Another object of this invention is to provide an anchored casing arrangement for an earth bore hole which is particularly useful for anchoring large diameter casing subject to a wide range of temperature variation.

These and other objects of the invention will be explained and an understanding of the invention will be had by referring to the following description and claims taken in conjunction with the attached drawings in which:

FIGURE 1 is a cross-sectional view of a casing anchored in the earth communicating with an underground cavern according to the principle of this invention.

FIGURE 2 is a cross sectional view of the anchored casing taken along the line 2—2 of FIGURE 1.

Referring to FIGURE 1, a casing 10 is shown supported in an earth bore hole 12 which communicates with an

2

underground cavern 13. The bore hole 12 is always larger in diameter than the external diameter of the casing 10, leaving an annulus 14. As previously indicated, the normal means of anchoring the casing is to fill the annulus 14, usually from the bottom of the casing to the surface of the earth, with a hard setting cement grout. While this method works completely satisfactorily for small diameter casing and particularly installations where relatively small ranges of temperature variations are encountered, such an arrangement has not proven satisfactory for large diameter casing subject to high temperature variations.

By the method of this invention, before inserting the casing into the bore hole 12, the upper portion thereof is covered with a lubricating compound layer 16. Such lubricating compound layer 16 may be of any material which will prevent a hard setting grout from adhering to casing 10 and includes the use of heavy grease or some similar material.

The lower portion of casing 10, such lower portion being designated by the numeral 18, is uncoated and may be especially prepared, if necessary, by cleaning or otherwise, so that hard setting cement grout will adhere to it. With the casing 10 in position in the bore hole, an anchoring strata of hard setting grout 20 is poured into the annulus 14 which serves to anchor the bottom of casing 10 to the walls of the bore hole 12. Next, a strata of chemical seal 22 is poured in the annulus 14. The chemical seal strata 22 rests upon the top of the anchoring strata 20. It contacts casing 10 and fills all of the exterior of the lower uncoated portion 18 above the anchoring strata 20.

Next, a stabilizing hard-setting grout 24 is poured to fill the annulus 14 between the lubricating coating 16 and the interior wall of the bore hole 12.

A plurality of anchoring bolts 26 are installed through the lower portion of casing 10 and into the wall of the earth bore hole 12. The anchoring bolts 26 extend through the anchoring strata 20.

Anchoring bolts 26 and the anchoring strata 20 combine to anchor the bottom of casing 10 to the earth with the casing 10 extending upwardly to the surface of the earth. The chemical seal 22 prevents leakage of subsurface water from flowing along the casing 10 and into the underground cavern 13.

The casing 10, being anchored only at the bottom, is free to contract and expand along its entire length to the surface. When the casing 10 is subjected to temperature change, the lubricative layer 16 permits free expansion and contraction in length so that no stress or strain is placed upon the casing or the stabilizing grout 24.

The anchoring grout 20 and the stabilizing grout 24 are of a hard setting material, such as cement.

The chemical seal strata 22 is composed of any material which remains fluid or at least plastic at the lowest temperature to which casing 10 will be subjected. In the instance wherein casing 10 is utilized to convey liquefied natural gas into an underground cavern 13, the chemical seal 22 must remain plastic to at least minus 260° F., the minimum expected temperature. When the casing 10 will be subjected to a smaller range of temperature variation wherein the lowest expected temperature is higher than that for liquefied natural gas, the liquid chemical seal 22 may be of greater variety of compounds. Thus, the selection of the material of which the chemical seal 22 is composed will be dependent upon the minimum temperature to which the casing 10 will be subjected.

This invention provides a greatly improved means of anchoring large diameter casing in a manner such that a continuous waterproof seal can be provided in a manner permitting the expansion and contraction of the casing without causing damage to the casing or to the stabilizing grout which supports the casing in the earth bore hole and without destroying the seal of the casing to the bore hole.

While this invention has been described with a certain degree of particularity, many changes may be made in the details of construction and the arrangement of components without departing from the spirit and scope of this disclosure.

What is claimed:

1. A method of anchoring and sealing a large diameter casing in an earth bore hole comprising
  - applying to the exterior of the upper portion of said casing a lubricative compound,
  - lowering the casing in the bore hole with the uncoated portion at the bottom,
  - pouring an anchoring strata of grout in the annulus between the lower portion of the uncoated portion of the casing and the bore hole,
  - pouring a strata of chemical seal in the annulus between the upper portion of the uncoated portion of the casing and the bore hole, the lower surface of the chemical seal strata resting upon the upper surface of the anchoring grout strata, and
  - pouring a grout in the annulus between the coated portion of the casing and the bore hole.
2. A method of anchoring and sealing large diameter casing according to claim 1 including the step of installing rock bolts between the casing and the earth bore hole wall through the anchoring grout.
3. An anchored casing in an earth bore hole comprising
  - a length of casing positioned in said bore hole,
  - an anchoring strata of hardsetting grout in the annulus

between the lower portion of the casing and the bore hole,

a strata of chemical sealing compound between the casing and the annulus, the chemical seal strata bottomed on the anchoring grout strata,

a layer of lubricating compound on the exterior of that portion of said casing above said chemical seal strata, and stabilizing hard setting grout in the annulus between said layer of lubricating compound and the bore hole wall above said strata of chemical sealing compound.

4. An anchored casing according to claim 3 including a plurality of rock bolts extending through the wall of said casing and into the wall of said bore hole, said rock bolts extending through said anchoring grout strata.
